Primary Examiner — Jack Reickel*Assistant Examiner* — Michael A Kervin(74) *Attorney, Agent, or Firm* — Hanley, Flight and Zimmerman, LLC(57) **CLAIM**

The ornamental design for a wall mount, as shown and described.

DESCRIPTION

FIG. 1 is an isometric view of a wall mount, showing our new design;

FIG. 2 is a rear view thereof;

FIG. 3 is a front view thereof;

FIG. 4 is a bottom view thereof;

FIG. 5 is a top view thereof;

FIG. 6 is a first side view thereof; and,

FIG. 7 is a second side view thereof.

Features shown in broken lines form no part of the claimed design.

1 Claim, 7 Drawing Sheets(56)
